ROTARY DIAZO WHITE PRINTER

Montgomery H. Robbins, Essex, Conn.

Application March 24, 1958, Serial No. 50,139

Term of patent 14 years

(Cl. D61—5)

Fig. 1 is a front elevational view of a rotary diazo white printer, showing my new design with the hinged door in closed position;

Fig. 2 is a top plan view;

Fig. 3 is a rear elevational view;

Fig. 4 is a bottom plan view;

Fig. 5 is an end elevational view;

Fig. 6 is an opposite end elevational view; and

Fig. 7 is a perspective view thereof, with the hinged door in open position.

I claim:

The ornamental design for a rotary diazo white printer, as shown.
